FRAMING MACHINE FOR LADIES' HAND-BAGS AND THE LIKE

Julian B. Rosenthal, Bronx, N. Y.

Application August 14, 1950, Serial No. 179,271

1 Claim. (Cl. 153—1)

1

This invention relates to improvements in presses for clamping handbag body materials to handbag jaws, particularly that type of press disclosed in my co-pending application, filed March 20, 1950, Serial Number 150,653.

The principal object of the invention is generally to improve such presses in a manner to facilitate their utilization in the manufacture of handbags.

Another object of the invention is to provide improved operating means for such presses whereby the same are operable with a minimum of effort in a minimum amount of time.

Still another object of the invention is to construct the press so as to provide for the operator's safety to the fullest extent.

A further object of the invention is to construct the press so that the same has a novel mode of operation particularly adapted to the manufacture of handbags.

A still further object of the invention is to construct the press so that the same is adapted to rapid readjustment for various types of handbag frames.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a general side elevation of the device with certain parts broken away to compress the figure.

Figure 2 is a plan view of the device.

Fig. 3 is a front elevation of the device.

Fig. 4 is a rear elevation of the device.

Fig. 5 is a fragmentary plan view with certain parts removed.

Fig. 6 is a front elevation with the parts removed in Fig. 5 removed here also.

Fig. 7 is a front to rear center sectional view of the device, taken on line 7—7 of Fig. 5.

Fig. 8 is a view similar to Fig. 7 but illustrates an operated position of the parts.

Fig. 9 is a fragmentary sectional view on line 9—9 of Fig. 2.

Fig. 10 is an isolated perspective view of the female die means.

Fig. 11 is an isolated perspective view of the male die means.

Fig. 12 is a perspective view of a cover member.

Referring to Figs. 1, 2, 3, 4, 7 and 8, the device of the invention includes a cast head member 15 which is configured to provide a sloping front, a recess 16, a rear extension 17 and mounting pads 18 by which the same is secured atop a suitable table 19.

Secured on the sloping front face of the casting 15, by means of Allen head cap screws or the

2

like, is a cover plate 20 provided with a laterally extending step 21 at its lower edge, see Figs. 1, 2, 9 and 11. Secured on said step by a single Allen head cap screw 22 is a male die member 23 which, as best shown in Figs. 2, 3 and 4, extends laterally beyond said cover plate in either direction. As shown, the sloping face of casting 15 is provided with an edging boss 24 at either side thereof; and it is to this boss that the cover plate 20 is secured.

Mounted on steps 25 cut in the bosses 24, underneath the cover plate 20, is a slide 26, see Figs. 5, 6 and 10. As best shown in Figs. 1, 2 and 3, the said slide projects downward and forward beyond the lower ends of the bosses 24 and the cover plate 20. Near its lower end the slide 26 is provided with a lateral groove 27 in which is secured by an Allen head cap screw an extrusion of a female die member 28. Referring to Figs. 1, 7, 8 and 10, it will be seen that the female die member 28 is provided with a concavely formed face 30 for cooperation with the male die member 23. The female die member 28 is, as best shown in Figs. 2 and 3, considerably shorter laterally than is the male die member. The reason for this will become apparent hereinafter.

In order that the slide 26 may be moved upwardly and rearwardly between the cover plate 20 and the steps 25 to effect the cooperation of the male and female dies, said slide is provided with an aperture 31, see Figs. 7, 8 and 10. Provided to fit in said aperture 31 is the forward arm 32 of an actuating lever 33 pivoted as at 34 in the casting 15. It will be seen that a clockwise movement of said actuating lever 33 will, through the engagement of the arm 32 thereof with aperture 31 move the slide 26 upward and rearward and effect the cooperation between the said male and female dies. However, as it is desired that the slide 26 normally be retained in its lower ineffective position, a coil spring 35 engages in a well 36 in the upper edge of the slide and tensions the same downward and forward, see Figs. 7, 8 and 10.

The other end of spring 35 is mounted on a short post 37, see also Figs. 5 and 6, which projects from a lower extension 38 of a plate 40 which extends across the upper portion of the recess 16 and is secured by bolts 41 to the casting 15. The lower extension 38 of said plate projects downward into the said recess, so that the post 37 is located as low as possible. As shown, the spring 35 does not extend in a straight line from the post 37 to the well 36 but rather in an arcuate line. The effect of the spring 35 remains the same however.

In order to cover the spring 35 and protect it from damage the means shown in Figs. 1, 2, 3 and 12 is provided. Such means comprises a cast cover member 43 having a pair of feet 44 which are secured atop the bosses 24 by suitable

bolts, and a cover plate 45 which extends downward and forward into abutting relationship with the cover plate 20 hereinabove described. At its lower end the cover plate 45 rests atop suitable extrusions 46 of the bosses 24. Cover member 43 also is provided with an extension plate 46 which engages between ears 47 of the casting 15 and covers the upper end of the recess 16.

It will be seen, therefore, that all of the operating mechanism is completely covered and that the operator of the device is fully protected therefrom.

In order to rock the lever 33 to effect the cooperation of the male and female dies as above described, there is provided a roller 48 carried by a short downward extension 50 of an operating arm 51, said extension being located an extremely short distance rearward of the pivot 49 of said arm to provide maximum leverage. The roller 48 engages an inclined plate 52 formed on the upper edge of the rearward arm of the actuating lever 33. Operating arm 51 extends rearward beyond the rear extension 47 of casting 15 and is provided with a plurality of holes 53 differentially spaced from the rearward end of the arm. Pivottally connected to the arm 51 by means of one of the holes 53 is a connecting rod 54 which extends downward and beneath the table 19 and is pivotally connected to a treadle or foot pedal 55, see Fig. 1. It will be seen that a downward movement of the treadle 55 will rock the operating arm 51 clockwise which will effect the clockwise rocking of the actuating lever 33 to thereby cause the slide 26 to move upward and bring the female die 28 into cooperation with the male die 23, as shown in Fig. 8. It will also be seen that the release of the treadle 55 will be effective to permit the spring 35, and a second spring 56 secured to the treadle, to return all of the elements to the normal positions illustrated in Fig. 7; and due to the system of high leverage provided, the amount of movement of the treadle that is required is small and is quickly attained, so that an operation of the device requires very little effort and consumes a very short period of time.

The purpose of providing the differential holes 53 is, of course, to provide for adjusting the leverage between the treadle 55 and the die members.

It is desired that movements of the female die 28 be adjustably limited in extent. To this end the operating arm is provided near its rear end with an adjustable limit screw 57 threaded into the under edge thereof and near its forward end with a second adjustable limit screw 58 threaded into the upper edge thereof, see Figs. 1, 7 and 8. The latter screw, by engagement with an upper cross bar 60 of the casting 15, determines the normal position of the female die 28 and, therefore, the extent of the gap between said female die and the male die 23. The screw 57, by engagement with a cross bar 61 of the rear extension 47 of the casting 15, limits the extent to which the treadle 55 can bring the die members together.

It will be seen, therefore, that by means of said adjusting screws the device is readily adjustable to handle handbag frames of various sizes and thicknesses. Also, in this regard it will be seen that the male and female die members are readily removed and replaced by others more ideally adapted to the work at hand.

The handbag frames adapted to be worked on

by the present apparatus are of U-shaped cross-section and are bent to form the outline of the handbag. Because of the inclined front of the device of the invention it is extremely convenient for the operator to place such a frame between the male and female die members and quickly bring the same together to compress the frame, it not being necessary to locate the frame in any accurate position between said dies due to the overlapping of the male die over the body portion of the female die; and due to the decreased size of the female die 28, clasps and the like secured on said frames can readily be protected from the dies. That is, such clasps can be located first on one side of the female die and then on the other to compress the frame adjacent said clasps.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a device of the class described, a head member having a recess and an open sloping front, a slide mounted in said recess immediately adjacent and parallel with said sloping front, a plate secured on said front and covering said slide, a step in the under edge of said cover plate, a male die member removably secured on said step, a female die removably secured on said slide below said male die, a well in the upper edge of the slide, a coil spring engaged in said well to maintain the slide in its lowest position, a plate extending across said recess above the slide, a post projecting from said plate, said spring also engaging said post, a cover member covering said open front above the first said cover plate, an aperture in said slide, an actuating lever pivoted in said recess and having an arm engaged in said aperture to raise said slide against the action of said spring and bring the dies into cooperating relationship when the lever is operated, an inclined plane formed on the upper edge of the other arm of said lever, an operating arm pivoted in said recess above said lever and extending rearwardly beyond said head, a downward extension of said arm located immediately to the rear of its pivot, a roller carried by said extension and engaging said inclined plane, a plurality of holes in said arm spaced differentially from the rear end thereof, a downwardly extending connecting rod pivotally connected to said arm by one of said holes, a treadle connected to the lower end of said connecting rod, means for adjusting the distance which said dies can be separated by said spring, and means for adjusting the extent to which the die members can be brought together.

JULIAN B. ROSENTHAL.
